UNITED STATES PATENT OFFICE.

RALPH L. FEAGLES, OF FORT WAYNE, INDIANA.

TOP FOR CONTAINERS.

Application filed September 17, 1926. Serial No. 136,019.

The invention relates to tops for containers and particularly to tops for milk cans.

The object of the invention is to provide a novel and sanitary one piece lid that effectively closes the container and has a maximum of strength and protects the container from injury from concussions or impacts on the lid.

Another object is to provide a lid that 10 may be readily restored to normal shape in case it may have been mashed or distorted in use.

Another object is to provide a lid that 15 will permit containers to be firmly stacked one upon another and thereby gain space in shipping or storing the containers.

Other objects and advantages will be set forth hereinafter.

The invention is illustrated in the accompanying drawings in which—

Figure 1 is an elevational view of a fraction of a container with the invention applied thereto; Fig. 2 a plan view of the lid; Fig. 3 an enlarged vertical cross-section 25 of the lid and container; Fig. 4 a cross section on line 4—4 of Fig. 2; Fig. 5 an end view of one of the reinforcements; Fig. 6 a cross section on line 6—6 of Fig. 2 and Fig. 7 a cross section on line 7—7 of Fig. 2.

In the illustrative embodiment of the invention the receptacle 1 is of any selected type but preferably of a type wherein the wall of the receptacle is free from corners or ledges that will not readily clean, the 30 illustrative receptacle having a restricted upper portion or neck 2 which curves gently into the lower cylindrical wall. A reinforcing band 3 is secured to the outer face of the neck adjacent to its mouth, and at each 35 of two diametrically opposite points on the band are two lugs 4 between each pair of which lugs is pivoted a lever 5 adapted to be engaged by a spring 6 that depends from the lid 7. This lever functions similarly 40 to the lever described in Patent No. 1,445,869 to Chalfant.

The lid 7 is formed of a single sheet of metal by pressing the material with suitable dies to form a slightly concaved top 8, a 45 gasket supporting channel 9 for the reception of a gasket 10 and a depending annular rim or flange 11. The rim or flange 11 fits within the mouth of the receptacle, and the upper end of the neck 2 and the upper 50 edge of the band project into the channel 9 and abut the gasket to seal the mouth

of the receptacle when the levers 5 are swung to a vertical position. The material is folded upon itself to form the channel 9 so that there is a double wall surrounding the upper 60 end or mouth of the receptacle and extending over its edge.

An opening 12 is formed in the rim or flange 11 that will vent the receptacle should any accumulation of gas therein be sufficient 65 to overcome the tension of the springs and raise the lid so as to expose the opening.

On the top surface of the lid are secured, preferably by spot welding, two relatively wide reinforcing plates 13 and 14 that project over the edge of the lid, the projecting portions being curved downwardly and outwardly and then curved downwardly and inwardly to form the beads 15 and 16. A slot 17 is formed in each projecting portion 70 of the plates and the material adjacent to the slot is fashioned into a tube 18 upon which tubes the springs 6 are hung or suspended. Radial reinforcing ribs 19 are 75 formed on each plate. These plates may 80 be cast or stamped or forged out of metal.

When the lid is applied to a container and the locking levers are turned downwardly considerable tension is placed on the 85 springs and strain is placed on the lid. The springs being engaged on the tubes 18 that are part of the relatively wide reinforcing plates the strain is so evenly distributed over the lid that the lid seats accurately and 90 in fluid tight manner on the receptacle and it retains its rigid condition.

What I claim is:

1. The combination of an open top container, a lid pressed from a single sheet of material having its edge portion folded upon itself and bent downwardly, the material of the lid extending beyond the said folded portion and being bent downwardly in spaced relation to the inner wall of said folded portion whereby to form a gasket receiving space, a gasket in said space, said space being adapted to also receive the mouth of the container, reinforcing members permanently secured to the lid and having portions extending downwardly over the side of the lid, supports formed in the extended portions of the reinforcing members respectively, means suspended on the support and means on the container to engage the suspended means for locking the lid on the container.

2. The combination of an open top con-

— tainer, levers pivotally mounted on the container adjacent to the top thereof, a concaved lid pressed from a single sheet of material having its edge portion folded upon itself and bent downwardly, the material beyond the folded portion being bent downwardly and spaced from the inner wall of the folded portion to form an annular gasket receiving space, a gasket in said space, 10 the said space also receiving the mouth of

the container, reinforcing plates permanently secured to the lid, the outer portion of each plate projecting downwardly over the side of the lid and having a support formed therein and a resilient member suspended on the support and adapted to engage any one of the levers. 15

In witness whereof I have hereunto signed my name this 31st day of August, 1926.

RALPH L. FEAGLES.
